UNITED STATES PATENT OFFICE.

JOSEPH R. PAYSON, SR., OF CHICAGO, ILLINOIS.

DESIGN FOR A LATCH-CASE.

SPECIFICATION forming part of Design No. 16,595, dated March 30, 1886.

Application filed March 17, 1884. Serial No. 124,721. Term of patent 7 years.

To all whom it may concern:

Be it known that I, JOSEPH R. PAYSON, Sr., a citizen of the United States, residing in Chicago, county of Cook, and State of Illinois, have invented and produced a new and original Design for a Latch-Case, of which the following is a specification, reference being had to the accompanying drawing, forming part thereof, and illustrating in perspective a latch-case in conformity with my design.

The latch-case A is rectangular in form, and has flat rectangular flanges B, which, projecting at a right angle to the sides of the case, is perforated with screw-holes. The rear end, D, of the case is inclined, and said incline merges into a pyramidal extension rising above the top C of the case, said pyramidal extension terminating in parallel lugs D², which are curved on their upper edges to produce a symmetrical appearance in connection with a scroll-handle, E, projecting from between the lugs, as shown, and having reverse curves F G, said handle being also partly concealed by the lugs, but has its main body projecting beyond the rear end of the case. The keeper I of the latch-case has a right-angle flange perforated to receive set-screws, and the keeper itself is substantially square in horizontal section, and has an inclined top, I', provided at its highest point with a rib, L, formed transversely of the keeper, and having beveled faces, the rear one of which may terminate in a curve, as shown.

In conclusion, it may be observed that the case and keeper, when together in position, form a pleasing design, for the reason that their

sides are in alignment with each other, and the inclination of the rear end of the case and the outer end of the keeper is substantially the same, the effect of which is not even materially marred by the fact of the slight difference in conformation of the cover of the keeper and case, and it may here be noted that the rib of the keeper may be omitted, and the cover of the case and keeper join each other in the same plane or at an inclination to the plane of their flanges.

Having described the distinguishing features of my design, what I claim is—

1. The design for a latch-case herein shown and described, the same consisting of the rectangular case provided with right-angular flanges, and having a pyramidal extension projecting above the top of the case.

2. The design for a latch-case herein shown and described, the same consisting of the rectangular case, the pyramidal extension rising above the case, and the scroll-handle projecting at an end from the pyramidal extension.

3. The design for a latch-case herein shown and described, the same consisting of a keeper and case rectangular in horizontal section, a pyramidal extension rising above the case, and a scroll-handle projecting at one end from the pyramidal extension and extending rearward from the same.

JOSEPH R. PAYSON, SR.
